METHINE DYES FROM INDAN-1,3-DIONE

Gether Irick, Jr., and James M. Straley, both % Tennessee Eastman Company, Box 511, Kingsport, Tenn. 37662

Filed Sept. 22, 1967. Published Dec. 17, 1968

Class 260—240

No Drawing. 14 Pages Specification

Novel water insoluble methine compounds prepared by condensing an indan-1,3-dione with an indolinylidene-acetaldehyde, a formyldiphenylamine, a formyltetrahydroquinoline, or a cinnamaldehyde are useful as dyes for hydrophobic textile materials. These compounds have the formula below:

wherein:

R is H, lower alkyl, lower alkoxy, halo or nitro
Y is a group of the formula

wherein R¹ is an alkyl or phenyl group, R² is lower alkyl, R³ and R⁴ are H, lower alkyl, lower alkoxy, halogen, lower alkylthio, lower dialkylamino, nitro or CN and R⁵ and R⁶ are lower alkyl.
